UNITED STATES PATENT OFFICE.

JOSEPH K. SHARPE, JR., OF INDIANAPOLIS, INDIANA, ASSIGNOR TO THE INDIANA MANUFACTURING COMPANY, OF INDIANAPOLIS, INDIANA, A CORPORATION OF WEST VIRGINIA.

FAN FOR PNEUMATIC STACKERS.

No. 902,842.

Specification of Letters Patent.

Patented Nov. 3, 1908.

Application filed May 7, 1908. Serial No. 431,321.

To all whom it may concern:

Be it known that I, JOSEPH K. SHARPE, Jr., a citizen of the United States, residing at Indianapolis, in the county of Marion and State of Indiana, have invented certain new and useful Improvements in Fans for Pneumatic Stackers, of which the following is a specification.

My invention relates to improvements in fans for pneumatic stackers such as shown and described in Letters Patent No. 717,565, issued December 30, 1902, to Albert A. Stelting, and consists in certain details of construction and arrangements of parts whereby I am enabled to simplify the construction thereof, and in means for insuring that the frictional driving element shall not cease its rotary motion prior to the cessation of motion of the driven element, and the uniform peripheral surface of said driving element thus maintained and undue abrasion or flattening of any portion thereof avoided by the otherwise continued rotation of the driven element, as will be hereinafter more fully explained.

The accompanying drawings illustrate my invention.

Figure 1 is a transverse vertical sectional view of a stacker fan and associated operating devices; Fig. 2, a bottom plan of the same; Fig. 3, a section of the ratchet pulley which may be employed in connection with said fan, and Fig. 4 a further detail of said pulley.

In the drawings, the portions marked 10 represent the upper and side portions of the casing of my improved stacker fan, the upper portion whereof is provided with an eye or ingress opening 11,—it being understood, of course, that said casing is permanently secured in the stacker structure and has a suitable hopper or straw chamber leading into its ingress opening, and also has a discharge outlet leading therefrom, as usual.

In a suitable bracket, 12, I mount the fan-shaft 13, to the upper end of which is secured the fan blades, 14, in any appropriate manner. The bottom, 15, of said fan casing is rigidly secured to said shaft 13, and has formed therewith or connected thereto about its periphery an upwardly-extending flange, 16, within which the casing 10 is closely fitted, said bottom being in the form of a friction disk designed to be rotated (and simultaneously therewith the fan blades) by

engagement with the friction wheel, 17, mounted on the shaft, 18, supported in suitable brackets, 19, or otherwise, and driven by the ratchet pulley, 20, such arrangement of friction disk and fan blades constituting a frictionally driven fan.

In order to produce variable speeds of disk 15 the friction wheel 17 is so mounted as to be moved along shaft 18, and this may be accomplished by any suitable means, that shown being a shifting rod, 21, mounted in suitable brackets, 22, 23, appropriately secured to the stacker frame, one end of said shaft being screw-threaded and provided with an internal screw-threaded hand-wheel, 24, a yoke, 25, being connected to the opposite end of said rod and secured to wheel 17, by the manipulation of which hand-wheel 24 said friction wheel 17 may be adjusted to the desired position on shaft 18. It will also be understood that the contact or pressure between said friction disk and friction wheel must be properly maintained at all times, and for such purpose I may provide any suitable pressure regulating means, that shown being a coiled spring, 26, secured on the end of shaft 13 by a set-nut, 27, by the adjustment of which nut the tension of said spring may be controlled, so that by increasing or diminishing such tension the frictional engagement between friction wheel 17 and disk 15 may be accordingly governed. The herein described means for producing variable speed of disk 15, and for regulating and maintaining the pressure between said disk and its driving wheel 17, are similar to those disclosed in said patent herein referred to and specifically described therein, but, as indicated, I may employ any appropriate means for such purposes.

The friction wheel 17, and the disk 15, may be of any suitable material, an efficient arrangement for the purpose being a driving wheel provided with a fibrous or other peripheral surface, and a smooth metal disk.

In compensating the speed and improving the operation of the stacker fan by the employment of friction driving means, it is highly important that the material thereof be protected from undue abrasion or flattening at any point, and for this purpose I provide the ratchet pulley, 20, on the end of shaft 18, of any appropriate construction for the purpose, that illustrated being of a well known and common form, being provided

with spring-controlled pawls, as 30, in the outer portion thereof, and a sleeve provided with an internal ratchet-head, 32, rigidly secured to shaft 18, the object and operation 5 of such ratchet pulley being to maintain constant speed rotation of friction wheel 17 without regard to the variable or intermittent initial driving power for the fan. By this arrangement when the initial driving 10 power is appreciably diminished or ceases, with a consequent effect upon the ratchet pulley, the ratchet sleeve by its momentum will disengage from the pawls and continue unvaryingly the rotation of shaft 18 and 15 friction wheel 17, so that said wheel 17 and disk 15 are in regular and constant rotary contact, thus insuring that the friction wheel shall not first cease to rotate, and the friction disk 15 by its momentum continue to rotate 20 for a period thereafter, which circumstance would cause that portion of the fibrous or other material on the otherwise immovable friction wheel contacting with said disk to become worn or reduced to a flat condition, 25 which, as will be readily understood, would render it unfit for use; and, therefore, by the application of suitable means, such as a ratchet pulley, for maintaining constant rotation of these elements independently of any 30 irregularity of speed of the prime motor or intermediate driving mechanisms for the stacker fan, I am enabled to prevent the uneven wearing or impairment of the friction pulley indicated.

35 I claim as my invention:

1. A fan for pneumatic stackers comprising a casing, a rotatable frictionally driven disk constituting the bottom of said casing, and fan wings associated with and rotating 40 with said disk for ejecting material from said fan.
2. A fan for pneumatic stackers comprising a flanged rotatable disk, a casing fitting within said flange, fan-wings associated with

said disk, and means for simultaneously rotating said disk and said fan wings.

3. A fan for pneumatic stackers comprising an upper rigid casing portion, a rotatable disk constituting the bottom of said casing, rotatable fan wings within said casing, a rotatable element engaging said disk for frictionally driving the same, and means for driving said element.

4. In a pneumatic stacker, the combination, with a fan structure comprising a rotatable bottom member, of means for frictionally driving said member, means for adjusting said driving means to vary the speed of said member, and means for rotating said driving means and maintaining constant rotative action between it and said member independently of the speed of any prime motor which may be employed.

5. In a pneumatic stacker, the combination of a fan casing, a fan therein, means for frictionally driving said fan, and means for maintaining said fan and frictional driving means in coincident rotary motion independently of the irregularity or cessation of speed of the initial driving means for said fan.

6. A pneumatic stacker fan comprising a rotary disk having fan wings associated therewith, means for frictionally rotating the same, pressure-regulating means for controlling frictional contact between said fan and 75 its rotating means, means for changing the speed of said fan, and means independent of the initial driving source of said fan for imparting motion to said rotating means and said fan and maintaining the coincident rotation thereof.

In testimony whereof I affix my signature in presence of two witnesses.

JOSEPH K. SHARPE, JR.
